HERMAN BAADER, OF MOUNTAINVILLE, PENNSYLVANIA, ASSIGNOR TO TEXTILE PATENTS CORPORATION, OF ALLENTOWN, PENNSYLVANIA, A CORPORATION OF DELAWARE

NARROW FABRIC LOOM

Application filed October 3, 1928. Serial No. 310,039.

This invention relates to narrow fabric looms used for making ribbon, tape and the like, and the invention is concerned more particularly with mechanism for driving the 5 shuttles of such a loom.

Narrow fabric looms as now commonly constructed, include a batten on which are mounted two rows of shuttles extending lengthwise of the batten. The shuttles in each 10 row are driven by means of a rack bar extending the length of the batten and engaging pinions mounted in the shuttle raceways, a pair in each raceway. These pinions engage rack teeth formed in the bases of the shuttles 15 and as the rack bar is reciprocated, the pinions oscillate and by their engagement with the shuttle teeth cause the shuttles to pass through the sheds. The rack bar is commonly reciprocated by mechanism which includes elliptic and eccentric gearings and 20 driving cranks connected to the rack bar by straps.

This construction has numerous objections, among them being lack of control over the 25 shuttle resulting from lost motion in the connections due to wear. The shuttles and the rack bar are commonly made of wood and these parts are not only affected by changes in humidity in the atmosphere but in addition 30 they wear rapidly and become loose. This lost motion results in the shuttles reaching the ends of their throws and rebounding, causing injury to the warp ends. Another objection is that the shuttles are of light 35 wood and they swell and shrink with weather changes, causing binding in the guideways, or looseness, which causes rattling and loss of control. Changes in atmospheric conditions 40 also affect the straps connecting the hank and the rack bar, producing variations in the throw of the shuttles.

A more important objection which results 45 from the use of this construction resides in the loss of space on the batten. Theoretically, each shuttle in such a loom should not be substantially longer than the width of the reed, so that the shuttle will just span the distance 50 between the ends of guide blocks forming aligned guideways on each side of the reed. It is necessary, however, to place the pinions,

of which there is one near each end of each guideway, at some distance inward from the ends of that guideway for structural reasons, and as each shuttle must be engaged with one pinion at one side of the reed before it leaves the pinion on the other side of the reed, the shuttle must have a length somewhat greater than the distance between the centers of the pinions, so that a continuous driving connection will be maintained. In this old 55 construction, the shuttles are therefore considerably longer than the theoretical requirement and as each raceway must be sufficiently long to receive the entire shuttle, it follows 60 that the reeds have to be separated a greater distance than would be necessary if the length of the shuttles could be reduced so that they would just span a reed. By reason of this 65 spacing of the reeds, the number of reeds and shuttles which can be mounted on a batten 70 of a given length is much less than the theoretical capacity of the batten, and the use of this driving mechanism for the shuttles 75 therefore results in an inefficient loom with respect to output, and the floor space 80 in the mill is consequently not used to its greatest capacity.

The shuttle motion of the present invention overcomes the objections encountered in the use of the rack and pinion drive above described, and this mechanism permits the batten to carry a number of shuttles closely approaching the theoretical maximum determined by the width of the fabric. The new mechanism also provides means for driving the shuttles so that these shuttles are under exact and positive control at all times and this mechanism is not affected by changes in weather conditions, thus avoiding damage 85 to the shuttles by reason of swelling or shrinking of the parts. With this new shuttle drive the shuttle speed may also be greatly increased.

In a loom embodying this new mechanism, 90 the shuttles are mounted in upper and lower rows lengthwise of the batten and associated with each row of shuttles is an actuator bar extending along the row and mounted for reciprocating and oscillating movement. 95 These bars are connected together at the ends 100

of the batten and are reciprocated and rocked during their reciprocating movement. Each bar is mounted so as to lie at one side of the row of shuttles between the front and rear edges thereof and each bar carries means for engaging the shuttles. These means preferably take the form of plates of quadrant form mounted rigidly on the bar, a pair for each shuttle, and the plates for each bar are offset substantially 90°. Each of the shuttles has a slot near each end adapted to be entered by plates and at the beginning of the shuttle movement, each shuttle is connected to the bar by a plate entering a slot at the trailing end of the shuttle. As the bar advances, each shuttle is moved through its shed and when its leading end projects from the shed, the bar is rocked to disengage the drive plate from the trailing end of the shuttle and to bring another plate in engagement with the leading end of the shuttle. This engagement continues until the shuttle has completed its throw and on the return movement the operations are reversed.

For a better understanding of the invention, reference may be had to the accompanying drawings, in which

Fig. 1 is a view in front elevation of a portion of a batten embodying the invention, only a few of the shuttles being illustrated and various parts being broken away;

Figs. 2 and 3 are sectional views on the lines 2—2 and 3—3 of Fig. 1, certain of the parts being shown in end elevation;

Fig. 4 is a diagrammatic view illustrating the operation of the device;

Fig. 5 is a view in perspective showing a portion of the actuator bar; and

Fig. 6 is a view similar to Fig. 1, showing a modified embodiment of the invention.

Referring now to the drawings, the batten is illustrated as comprising a beam 10 and an upper rail 11, these parts being connected by straps 12 on which guide blocks 13 and 14, defining shuttle raceways in upper and lower rows, are mounted in the usual manner. Preferably, the blocks are of two kinds, the single blocks 13 extending between a pair of strap members and defining one wall of a raceway, while the double blocks 14 extend across and are connected to four of the strap members, each double block forming a wall of a pair of raceways, one on each side of the space 15 in which a reed is mounted.

The shuttles 16 mounted in the raceways are preferably of the construction set forth and claimed in my co-pending application Ser. No. 310,041, filed Oct. 3, 1928. Each shuttle consists of an open frame in which is mounted a quill and a base plate 17 attached thereto and lying within the shuttle raceway. The frame portion of each shuttle has a slot 18 near each end, this slot being open at both ends and having a curved bottom wall as in-

dicated at 18' in Fig. 2. The shuttles are mounted in the two rows in such manner that the shuttles in the upper row have their slots in their upper sides and those in the lower row have their slots in their lower sides.

Disposed above the top row of shuttles and lying between the forward and rear ends of the shuttles is an actuator bar 19. This bar is mounted in brackets 20 which may be attached to a slide 21 movable in a suitable channel in the upper rail 11. The bar is mounted loosely in the brackets for free oscillating movement, but carries collars 22 on each side of each bracket so that as the slide 21 is reciprocated endwise, the rod will be carried with it. Below the lower row of shuttles is a similar bar 19 mounted in brackets 23 attached to a slide bar 24, this actuator bar also having collars 22 on each side of each bracket, so that the rod is positively connected to the slide bar 24 to be moved therewith. The slide bars 21 and 24 are supported at one end in brackets 20, 23 connected to slides 25 disposed at one end of the batten. Between the slides 25 extend rods 26, and between these rods lies the end of a lever 27, which can be swung by appropriate mechanism such as that shown in Letters Patent #1,731,286, granted to me Oct. 15, 1929, to cause the slides and the actuator bars to be reciprocated endwise during the operation of the looms.

Each actuator bar carries a plurality of pairs of elements 28, one pair for each shuttle, by which the bar can be connected to the shuttles. These elements are preferably in the form of quadrant plates, as illustrated in Fig. 5, and the plates of each bar are offset angularly substantially 90°. Each pair of plates is disposed on the actuator bar with an interval between corresponding to the intervals between slots in the opposite ends of a shuttle. At its end, each bar carries a bevel pinion 29 meshing with a bevel gear 30 on a stud shaft 31 journaled in a part of a slide 25 and on the end of each stud shaft is a fork 32 adapted to straddle a pin 33 carrying a roller 34, the pins 33 being mounted on fixed parts of the batten.

With this construction, the shuttles are moved in the manner illustrated in the fragmentary view of Fig. 4, in which a single shuttle and a part of the operating mechanism therefor are illustrated. It will be understood that in the complete loom, these parts are duplicated many times, but an explanation of the operation of a single shuttle will make clear how all of the shuttles are driven. At the beginning of the shuttle movement in one direction, as for example, to the right in Fig. 4, a shed has been formed in the warp threads passing through the reed in the space 15. The shuttle is now moved by engagement of the plate 28a in the slot at the trailing end of the shuttle and as an actuator

bar is moved toward the right it carries the shuttle with it, the leading end of the shuttle passing into and through the shed. When the leading end of the shuttle enters the raceway at the right of the reed, the actuator bar begins to oscillate, this movement being brought about by the engagement of one of the forks 32 with its pin 33. In the first part of such oscillation, the slots in each end 5 of the shuttle are engaged by plates 28, but as the oscillation is completed, the plate which was previously engaged with the slot in the trailing end of the shuttle is freed completely from that slot, while the plate 28b 10 at the leading end of the shuttle completes its engagement with the slot in that end. The movement of the shuttle to the end of its throw is then continued by engagement of the plate at the leading end of the shuttle 15 with its slot. In the return movement of the parts, the operations are reversed. Accordingly, each shuttle is moved by a plate 28a at the beginning of its throw, while the adjacent plate 28b is in such position that it is free 20 to pass beneath the warp ends forming the sheds and can do no injury thereto. When the actuator rod is moved past the reed and the plate 28b can be brought into operation without damage to the ends, the rod is rocked. 25 In such movement, the plate 28a is moved to a position shown at the bottom in Fig. 4, where it can pass beneath the ends without touching them. Since the shuttle is engaged by one or the other or both plates 28 through- 30 out its throw and is thus positively connected to the actuator bar, the shuttle is under complete control at all times, and cannot rebound when the end of its throw is reached. The parts by which the shuttle is operated are 35 kept from contact with the warp ends so that no injury to them can occur and these parts may all be made of metal, so that wear takes place only very slowly. Damage occurring due to swelling and binding of the parts is 40 avoided by making the guide blocks of metal and using shuttles of the construction described in my application above referred to, in which that part of the shuttle which takes up the wear and moves in the guideways in 45 contact with the blocks is made of fibre.

It will be seen that with this new drive mechanism, each shuttle has a length only slightly greater than the distance between a pair of aligned guideways on each side of the 50 reed and this excess length need only be sufficient to insure that the leading end of the shuttle may be seated in its guideway before the trailing end leaves the other guideway. The plates 28 are placed on the rod a distance 55 apart corresponding to the distance between the slots in the shuttles and each plate is opposite the slot in one end of the shuttle. Due to the fact that the shuttles and their guideways may be of less length for a given width 60 of fabric that would be required in the case

of shuttles and guideways for the same fabric width actuated by the rack and pinion drive, a greater number of reeds can be mounted on a standard size batten and therefore the productivity of the loom is increased. Also 70 by reason of the better control of the shuttles and the metal construction of the driving parts, the shuttle speed can be greatly increased, thus further increasing the loom output. 75

In Fig. 6 there is shown a slightly modified means for driving the actuator bars in which the bars are shown as mounted at one end in the brackets 20 and 23 and slides 25 reciprocated in the batten by any suitable means, and at their other ends the rods enter tubes 35 in which cam slots 36 are formed. Each rod carries a pin 37 entering the slot. With this arrangement, reciprocation of the slides 25 causes the endwise movement of the rods and the engagement of the pins in the slots in the tubes 35 causes the oscillation of the rods at the proper instants. 85

This application is a continuation in part 90 of my co-pending application Ser. No. 208,- 918, filed July 28, 1927.

I claim:

1. In a loom, the combination of a plurality of shuttles mounted in two rows, a pair 95 of bars disposed at opposite sides of the rows of shuttles and lying between the front and rear ends of the shuttles, said bars being mounted for lengthwise and oscillating movements, a plurality of pairs of shuttle driving elements rigidly mounted in pairs on the bars one pair for each shuttle, the elements 100 of each pair being angularly offset, and means for reciprocating the bars and oscillating them during their reciprocating movement whereby each shuttle is moved successively 105 by the elements of the pair associated with it.

2. In a loom, the combination of a plurality 110 of shuttles mounted in a row, a bar disposed at one side of the row of shuttles and lying between the front and rear ends of the shuttles, this bar being mounted for lengthwise and oscillating movements, a plurality of pairs of plates of quadrant form rigidly mounted on the bar, a separate pair for each shuttle, the plates of each pair being offset at least 90°, and means for reciprocating the bar and oscillating it during its reciprocating movement to cause the plates successively to engage and drive the shuttles with which they 115 are associated. 120

3. In a loom, the combination of a plurality 125 of shuttles mounted in a row, a bar disposed adjacent the row and extending lengthwise thereof, a plurality of plates rigidly mounted in pairs on the bar, a separate pair for each shuttle, these plates being of quadrant shape and those of each pair being angularly offset on the bar whereby they may be engaged successively with their associated shuttle on oscillation of the bar, and means 130

- for reciprocating the bar and oscillating it during its reciprocation.
4. In a loom, the combination of a batten, a plurality of shuttles mounted thereon in upper and lower rows extending lengthwise of the batten, a separate bar disposed at one side of each row of shuttles between the forward and rear ends of the shuttles in the rows, means rigidly carried by the bars for engaging and driving the shuttles, a connection between the bars, and means for reciprocating the bars in unison and oscillating them during their reciprocation. 70
5. In a loom, the combination of a batten, a plurality of shuttles mounted thereon in upper and lower rows extending lengthwise of the batten, a separate bar disposed at one side of each row of shuttles between the forward and rear ends of the shuttles in the rows, the rows of shuttles lying between the bars, means rigidly carried by the bars for engaging and driving the shuttles, a connection between the bars, and means for reciprocating the bars in unison and oscillating them during their reciprocation. 75
6. In a loom, the combination of a plurality of shuttles mounted in upper and lower rows, a separate bar disposed at one side of each row of shuttles, plates carried rigidly by the bars adapted to engage and drive the shuttles and means for reciprocating the bars in unison. 80
7. In a loom, the combination of a plurality of shuttles mounted in upper and lower rows, a separate bar disposed at one side of each row of shuttles, plates carried by the bars, a pair for each shuttle, these plates being rigidly mounted on the bar with the plates of each pair angularly offset and adapted on 85

slide bar for oscillation but held against end-
wise movement relative thereto, a plurality
of plates fast on the actuator bar for engaging
and moving the shuttles there being a sepa-
5 rate pair of plates for actuating each shuttle,
the plates being brought alternately into ac-
tion on rocking of the said bar, means for
reciprocating the slide bar, and means for
10 oscillating the actuator bar during recipro-
cation of the slide bar.

15. In a loom, the combination of a batten,
a plurality of shuttles disposed thereon in
raceways for the shuttles mounted in the
batten, a bar disposed on the batten at one side
15 of the shuttles and movable lengthwise, this
bar lying in front of the plane in which the
raceways lie, means for reciprocating the bar
and oscillating it during its reciprocation and
means carried rigidly by the bar for engaging
20 and driving the shuttles, there being a sepa-
rate means for driving each shuttle, these
means being disposed in spaced relation and
being rendered alternately effective as the
bar is moved.

25. 16. In a loom, the combination of a batten,
a shuttle mounted movably thereon and hav-
ing a pair of recesses in one face, a bar mov-
able lengthwise and parallel to the path of
shuttle travel, this bar lying adjacent the face
30 of the shuttle in which the recesses are formed,
plates of quadrant form carried rigidly by the
bar and adapted upon movement thereof to
enter the recesses in the shuttle, there being
separate plates for each shuttle, means for
35 reciprocating the bar lengthwise, and means
for rocking the bar at selected intervals in its
reciprocating movement to cause the quad-
rant plates alternately to enter the shuttle
recesses.

40. In testimony whereof I affix my signature.
HERMAN BAADER.
